US00D984394S

(12) **United States Design Patent** (10) Patent No.: **US D984,394 S**
(45) Date of Patent: **** Apr. 25, 2023**

(54) **REMOTE CONTROL FOR HOME NETWORK**

(71) Applicant: **LG ELECTRONICS INC.**, Seoul (KR)

(72) Inventors: **Jeeyoung Yeon**, Seoul (KR); **Heejae Kwon**, Seoul (KR); **Sehwan Bae**, Seoul (KR)

(73) Assignee: **LG ELECTRONICS INC.**, Seoul (KR)

(**) Term: **15 Years**

(21) Appl. No.: **29/780,873**

(22) Filed: **Apr. 27, 2021**

(30) **Foreign Application Priority Data**

Oct. 30, 2020 (KR) 30-2020-0052267

(57) **CLAIM**

We claim the ornamental design for a remote control for home network, as shown and described.

DESCRIPTION

FIG. 1 is a front perspective view of a remote control for home network showing the new design;

FIG. 2 is a rear perspective view thereof;

FIG. 3 is a front view thereof;

FIG. 4 is a rear view thereof;

FIG. 5 is a left-side elevation view thereof;

FIG. 6 is a right-side elevation view thereof;

FIG. 7 is a top plan view thereof; and,

FIG. 8 is a bottom plan view thereof.

1 Claim, 8 Drawing Sheets
